[57] CLAIM

The ornamental design for a cup, as shown.

DESCRIPTION

FIG. 1 is a top plan view of a cup showing my new design;

FIG. 2 is a side elevational view thereof;

FIG. 3 is an end elevational view thereof;

FIG. 4 is a bottom plan view thereof; and

FIG. 5 is a partial sectional view at an enlarged scale taken along line 5—5 of FIG. 1.
